GOLF GAME BOARD FOR POOL TABLE PLAY

Lawrence R. Hermes, 1145 Atwood Ave.,
Cincinnati, Ohio 45224

Filed Mar. 13, 1968, Ser. No. 10,984

Term of patent 14 years

(Cl. D34—5)

FIG. 1 is a top plan view showing my new design for a golf game board for pool table play.

FIG. 2 is a side elevational view.

FIG. 3 is a section taken on line 3—3 of FIG. 1.

FIG. 4 is a fragmental section taken on line 4—4 of FIG. 1.

The dominant features of my design reside in the full line portions shown.

I claim:

The ornamental design for a golf game board for pool table play, as shown and described.
